Attorney

UNITED STATES PATENT OFFICE

WILLARD A. SINKLER, OF ADA, KANSAS

WEAR-HOOK BUCKLE ATTACHMENT

Application filed October 22, 1928. Serial No. 314,076.

This invention relates to harness and means for making a set thereof without sewing. More specifically, it is an attachment whereby all harness straps may be readily united or separated or adjusted and includes means for preventing chafing or wearing of the leather, as leather to metal connections are dispensed with.

Hitherto harness has been made by sewing and many leather to metal connections have been used. These two disadvantages have been obviated by my invention and new advantages presented as well. Sewed harness was not only non-adjustable but was easily ripped by accident or temporarily unusual strain. In addition the leather to metal connections caused undue wear on the leather with consequent short life thereof.

The present invention overcomes these difficulties. Metal to metal connections are used and the straps are not sewed. Longer life, ready adjustability, and easy substitution and repair of parts are thus provided.

Although the objects and advantages of the invention will be apparent as the disclosure proceeds, among them are the following: the provision of metal to metal connections ensuring longer life to the harness; the provision of a harness requiring no sewing; the provision of a harness readily adjustable and adaptable to circumstances of use; and the provision of a connection utilizable at many points but with the same underlying principle involved.

By way of example, the preferred embodiment of my invention, as well as illustrative secondary connections, are shown in the accompanying drawing wherein

Figure 1 is a view of one face of a connection in which is a connecting element and a strap of the harness.

Figure 2 is a cross section on the line 2—2 of Figure 1;

Figure 3 is a view of the opposite side of Figure 1;

Figure 4 is a view corresponding to Figure 3 without the connecting element and strap;

Figure 5 is a cross section on the line 5—5 of Figure 4;

Figure 6 is a view corresponding to Figure 1 without the connecting element and strap;

Figure 7 is a cross section of a device used in another location; and

Figure 8 is a cross section of a device used in still another location.

Referring to the drawings, wherein similar numerals refer to similar parts throughout the several views, a device is clearly shown alone, and used in various locations in a harness. It is cast as a unit out of any suitable material, generally metal, however, and comprises a central body portion 1 thickest near its center and gradually tapering off at top and bottom as shown. The upper end terminates in an integral hook 2 and the lower end rounds off to a much thinner portion 3. Rising from the sides of the casting are loop members 4, 5, 6, and 7.

If the face of the device be considered the surface on the same side with the open hook, the loops 4 and 5 will be seen to be on that side. The loops 6 and 7 are on the reverse side. It will be observed that loops 4 and 5 are nearer together than loops 6 and 7 and also that the latter loops extend higher up and lower down on the body than the former.

The body 1 is also provided with a transverse hole 8 in which can be placed the headed pin 9 as shown for a purpose hereinafter explained. The pin is longer than the hole so that its free end projects therebeyond.

The numeral 10 designates a connecting element which is so proportioned as to permit it to be snapped in under the free edge of the hook 2 and to be retained against easy displacement. The strap of the harness is designated by 11 and it should be noted in passing that the device can be made of any size to receive any width or thickness of strap.

Due to the construction of the device, surfaces 15 are provided (see Figure 5) which act as guides for the straps; the loops retaining in position the thus guided straps. A slot like hole 16 is thus formed by loops 5 and 7. A hole 17 is provided in the strap as will be understood to receive the projecting end of the pin 9.

It is thought that the assembly and operation will be clear from the nature and function of the parts but brief recapitulation will be made at this point. The connecting element 10 is first snapped in under the hook 2. The pin 9 is then placed in the hole 8, there being a portion of the pin projecting beyond the body member because the pin is longer than the thickness of said body. A harness strap end is then passed up under loops 7 and 6 in the order named, over the hook with the connecting element therein and then down under loops 4 and 5 in the order named. The hole in the end of the strap is so placed that the projecting end of the pin enters therein or may be guided therein by slight pressure or manipulation. Thus a connection is simply and easily made. The connecting element and the hook form a metal to metal connection which takes direct stress off the harness thus adding to the life thereof.

The device of my invention can be used in various locations in harness and the preferred form above explained in detail may be used in the reins, for example, where a connection to the bit is required.

Other locations can equally well utilize the invention and many connections in the harness are improved in the above manner. The connection at the neck yoke strap is well adapted and in that case no sewing is required and a metal to metal connection is similarly made. Again at the breeching hold back, the invention finds utility. The invention is also useful as a trace carrier connection and for the breeching carrier strap.

It will further be observed that the invention may be used either with or without the pin 9. By discarding the pin the device can be used anywhere as a wear hook and by using the pin it forms a buckle attachment with a metal to metal wear hook all in one.

Illustrative of further uses than the preferred one of Figures 1 to 6, inclusive, the forms of Figures 7 and 8 may be considered.

In Figure 7, the same unitary casting is shown with its hook and loops. Snap hook 10' is shown therewith. Although no hole is shown through the body member, it is understood that all devices are so provided but that the pin need not be used for purely a wear attachment as slipping of the strap may be permitted. The strap 12 passes under loop 7, 6, over hook 2, in which is hook 10', and under loops 4 and 5 as clearly shown.

Figure 8 shows another use similar to Figure 7 yet in which is shown the hole 8 and pin 9, the pin passing into a hole 17 in the strap 13. In this case another strap 14 is interposed between the strap 13 and the body member of the attachment, said strap having also a hole through which pin 9 passes to anchor the same.

All the above is intended to be more illustrative than limitative so that I do not limit

myself thereto, it being understood that the attachment serves for all wear connections, for anchoring strap ends, shortening or lengthening straps and the like, except as contained in the subjoined claims.

Having thus described my invention and illustrated its use, what I claim as new and desire to secure by Letters Patent of the United States is:

1. In a device of the character described, a casting comprising a solid central ellipsoidal body portion tapering into an integral hook and a plurality of loop members on each side thereof, the loop members on one side being further apart than the loop members on the other side.

2. In a device of the character described, a casting comprising a solid central ellipsoidal body portion tapering into an integral hook and a plurality of loop members on each side thereof, the loop members on one side being further apart than the loop members on the other side, said last named loop members being within the limits of the loops on the other side.

3. In a device of the character described, a solid ellipsoidal casting comprising a central body portion and a plurality of loop members on each side thereof, the loop members on one side being further apart than the loop members on the other side, said central body portion being thickest near its mid-portion and tapering toward both ends there being an integral hook at one end and a hole through the mid-portions, a pin in the hole longer than the thickness of said mid-portion and a connecting member on the hook, a strap having a hole therein passing under the loops which are further apart, over the hook and the portion of the connecting member lying therewithin, and under the loops which are nearer together, the projecting portion of the pin entering the hole in the strap.

In testimony whereof I hereunto set my hand this 16th day of October, 1928.

WILLARD A. SINKLIER.
